UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

RECEIVER FOR WIRELESS TELEGRAPHY.

Application filed July 9, 1921. Serial No. 483,493.

(GRANTED UNDER THE PROVISIONS OF THE ACT OF MARCH 3, 1921, 41 STAT. L., 1313.)

To all whom it may concern:

Be it known that I, HENRY JOSEPH ROUND, a British subject, of Marconi House, Strand, London, W. C., England, have made 5 certain new and useful Improvements in Receivers for Wireless Telegraphy (for which I have filed applications in Great Britain, Nov. 28, 1913, Patent No. 27,480 of 1913; 10 Belgium, July 5, 1920; France, July 1, 1920; Japan, July 7, 1920; Poland, July 8, 1920; Canada, July 10, 1920; Brazil, July 2, 1920; Germany, June 22, 1920; New Zealand, June 22, 1920; Trinidad, May 31, 1920; 15 India, July 9, 1920; Australia, June 15, 1920; Ceylon, June 2, 1920; Italy, June 7, 1920; Portugal, May 18, 1920; Tobago, May 31, 1920), of which the following is a specification.

This invention relates to improvements in 20 receivers for wireless telegraphy and has for its object the elimination of atmospherics.

It is well known that an atmospheric, being highly damped, causes the receiving circuits to oscillate at their own natural 25 frequency and cannot therefore be eliminated by tuning these circuits. It is also well known that if an oscillatory potential of a certain frequency be induced in an oscillatory circuit of a different natural frequency two sets of oscillations are produced 30 in that circuit, namely a transient free oscillation of the natural frequency of the circuit and a forced oscillation of the frequency of the induced potential, the latter 35 oscillation being transient if this potential is caused by damped waves and permanent, if it is caused by undamped or continuous waves.

According to the present invention I make 40 the natural frequency of the receiving aerial different from that of the received waves so that both the forced and the free oscillations occur producing the well known phenomenon of beats and I rectify the resultant 45 current and carry it to a circuit tuned to the beat frequency and I may directly or indirectly connect a telephone to this tuned circuit. The oscillations produced by an atmospheric last for a very short time, 50 and in order that they shall not affect the circuit tuned to the beat frequency, it is necessary for this frequency to be comparatively high so that several beats may occur

before the oscillations due to the atmospherics die out. Where this necessitates the 55 beat frequency being above the limit of audibility it is necessary to employ one of the well known devices for causing these beats to produce audible indications as for example a rectifier, or in the case of continuous waves a ticker or the generation of another frequency which will interfere with the inaudible frequency and produce beats of an audible frequency.

Where such a device is used for receiving 60 continuous or nearly continuous waves, it is obvious that the transient free oscillations of the aerial will not produce effective beats with the continuing forced oscillations, and in such cases it is desirable to generate a continuous oscillation of a frequency which is different from that of the forced oscillations and may be equal to the natural frequency of the aerial. These locally produced oscillations will interfere with the forced oscillations and produce the required beat 65 frequency, while they either will not interfere with the free oscillations produced by atmospherics or will produce an entirely 70 different beat frequency which will not affect the tuned circuit.

The rectifiers employed should not reach a condition of saturation so that the oscillations due to the received waves may not be impaired by simultaneous oscillations due 75 to atmospherics, the method of elimination depending upon the production by oscillations having slightly different frequencies of beats having widely different frequencies 80 one of which can be detected independently 90 of the other.

In the accompanying diagrams illustrating 95 my invention Fig. 1 is a diagrammatic representation of a receiving circuit in accordance with the invention, and Figs. 2 and 3 are similar views of modifications.

In Figure 1, A is the aerial slightly out of tune with the incoming signal waves. B is a circuit which is coupled to the aerial and which is preferably aperiodic. D is a circuit connected to the circuit B through a rectifying crystal C and tuned to the frequency of the beats due to the forced and free oscillations and T is a telephone inductively coupled to the circuit D.

With such a simple arrangement however

it may be difficult to get the beat frequency unaffected by atmospherics and yet low enough to be within the limits of audibility and to obviate this difficulty I may employ 5 the arrangement illustrated in Figure 2. A B C D are the same as before but D is now coupled through an intermediate circuit E to a circuit B¹ in which oscillations can be induced by means of a local oscillation circuit F¹ of such a frequency as to interfere with the oscillations in D producing beats of a frequency within the limits of audibility. The circuit B¹ is connected 10 through a second rectifier C¹ to a circuit D¹ connected to a telephone.

Figure 3 is similar to Figure 1 except that a local oscillation circuit F is provided for generating continuous oscillators in B for interfering with the forced oscillations 20 in the aerial when continuous oscillations are employed for signalling. The frequency of the oscillations induced in circuit D by circuit F may be equal to the natural frequency of the aerial.

25 Having described my invention, what I claim:

1. In a receiver for wireless telegraphy the combination of an aerial slightly out of tune with the signal waves, means for rectifying the resultant current due to the forced and free oscillations in the aerial and a circuit tuned to the beat frequency.

2. In a receiver for wireless telegraphy the combination of an aerial slightly out of 35 tune with the signal waves, a circuit coupled to the aerial, means for generating in that circuit oscillations of a frequency slightly different from that of the signal waves, means for rectifying the resultant current and a circuit tuned to the beat frequency.

3. A method of eliminating the results of atmospherics in wireless telegraph receivers, which consists in the production by 45 oscillations having slightly different frequencies of beats having widely different frequencies.

4. A method of eliminating the results of atmospherics in wireless telegraph receivers which consists in the production of a frequency interfering with the received frequency, rectifying, inducing a frequency interfering with the resultant oscillations and rectifying again.

5. In a radio receiving system, the combination of an aerial slightly out of tune with the signal waves, a receiving circuit coupled thereto, a circuit tuned to a frequency equalling the difference between the aerial frequency and the signal frequency, 50 and rectifying means between said circuits.

6. In a radio receiving system, the combination of an aerial slightly out of tune with the signal waves, a receiving circuit coupled thereto, a circuit tuned to a frequency equalling the difference between the 65

aerial frequency and the signal frequency, rectifying means between said circuits and indicating means associated with the last mentioned circuit.

7. In a radio receiving system, the combination of high frequency circuits comprising an aerial slightly out of tune with the signal waves, a receiving circuit coupled thereto, a source of local oscillations coupled to the high frequency circuits, a low 75 frequency circuit tuned to a frequency equaling the difference between the aerial frequency and the signal frequency, and rectifying means between said receiving circuit and said low frequency circuit.

8. In a radio receiving system the combination of high frequency circuits comprising an aerial slightly out of tune with the signal waves, a receiving circuit coupled thereto, a source of local oscillations coupled to the high frequency circuits, a low frequency circuit tuned to a frequency equaling the difference between the aerial 85 frequency and the signal frequency, and rectifying means between said receiving circuit and said low frequency circuit.

9. In a radio receiving signal system, the combination of high frequency circuits comprising an aerial slightly out of tune with the signal waves, a receiving circuit coupled thereto, a source of local oscillations coupled to the high frequency circuits of the same order of magnitude as the frequency of high frequency circuits, a low frequency circuit tuned to a frequency equaling the 100 difference between the aerial frequency and the signal frequency and rectifying means between said receiving circuit and said low frequency circuit.

10. In a radio receiving signal system, the combination of high frequency circuits comprising an aerial slightly out of tune with the signal waves, a receiving circuit coupled thereto, a source of local oscillations coupled to the high frequency circuit having a frequency substantially equal to the aerial frequency, a low frequency circuit tuned to a frequency equaling the difference between the aerial frequency and the signal frequency and rectifying means between said receiving circuit and said low frequency circuit.

11. A method of eliminating atmospheric interference in radio reception which consists in causing the said signal and atmospheric effects to produce oscillations of two different frequencies, superimposing a local frequency on said oscillations of a frequency adapted to produce beats of different frequencies therewith and selecting the 110 beat frequency produced between the signal and the local oscillations.

12. A method of eliminating atmospheric interference in radio signaling which consists in slightly detuning the aerial to cause 130

the signal and atmospheric effects to produce oscillations of two slightly different frequencies, superimposing a local frequency on said oscillations of a frequency adapted 5 to produce beats with said oscillations of different frequencies and selecting the beat due to the signal and local oscillation.

13. A method of receiving radio signals which consists in causing the received effects to produce oscillations of two different frequencies, rectifying the beats between 10 said oscillations, superimposing a local fre-

quency on the resultant beat frequency and rectifying again.

14. A method of receiving radio signals 10 which consists in causing the received effects to produce oscillations of two different frequencies differing from each other so as to produce inaudible beats, rectifying the beats between said oscillations; superimposing a local frequency on said inaudible beats adapted to produce therewith an audible beat frequency and rectifying again. 20

HENRY JOSEPH ROUND.
